WATER VAPOR GENERATING SYSTEM

Ellis H. Wilkinson, Neola, W. Va., assignor, by direct and mesne assignments, of one-fourth to Mary E. Schofield and one-fourth to Bessie C. Schofield, both of Philadelphia, Pa., and one-half to Florence May Wilkinson, Neola, W. Va.

Application August 26, 1932, Serial No. 630,580

10 Claims. (Cl. 122—5.5)

This invention relates to new and useful improvements in steam or other vapor generating systems and has particular relation to steam or other vapor generating systems wherein water saturated vapor is passed into a heating chamber and raised to a high degree of temperature for heating or other power purposes.

The principal object of the invention is to provide a water vapor generating system wherein air or other gaseous medium is first saturated with water and then passed to a heat chamber where the temperature of the vapor may be raised sufficiently to convert the vapor into steam.

Another object of the invention is to provide a vapor generating apparatus having novel means for saturating air or other gaseous medium with water prior to entrance of said vapor into the heat chamber.

Another object of the invention is to provide a vapor generating system involving the principle set forth which may be used in conjunction with the ordinary heat producing fuels as well as electricity.

Another object of the invention is to provide a vapor generating means as stated which may be used to lower the temperature of saturated vapors passing therethrough for cooling purposes in addition to raising the temperature thereof for heating or other power purposes.

Another object of the invention is to provide a vapor heat transfer system as described which does not require constant attention during operation and will materially reduce fuel operating costs as compared with similar operating costs where heat is applied directly to the liquid which must be raised as a mass to the temperature to produce steam.

Other features and details of the invention are set forth hereinafter and disclosed in the accompanying drawings, in which:

Fig. 1 is a view in side elevation of a vapor generating plant embodying the principle which is the subject of the present invention;

Fig. 2 is a diagrammatic view of a heat chamber for saturated vapor wherein an electric current is the heat producing medium;

Fig. 3 is a view similar to Fig. 2, wherein refrigerating coils have been used in place of the resistance heaters for cooling the air for ventilating purposes; and

Fig. 4 is an enlarged fragmentary section showing the construction of the spray and Venturi section.

Heretofore in generating steam or other vapors

for heating or power purposes, it has been the general practice to apply the heat directly to the water or other liquid from which the vapor is to be generated, but to my knowledge no vapor generating system has been produced wherein a saturated vapor is fed to a heat chamber at relatively low temperature and converted from that state into steam or other vapor at relatively high temperatures.

By the present invention vapors at substantial pressures and high thermal efficiency at saturated or superheat temperatures may be generated at a fuel cost approximating less than one-third the cost of fuel to generate vapors having the same thermal qualities in accordance with the principles of vapor generation in use up to the present time.

Referring now more particularly to the drawings, the present apparatus comprises an ordinary fire tube boiler 1 and superheat chamber 2, arranged within an insulated boiler casing 4, which is provided with conveniently arranged baffles 4a directing the flow of the hot combustion fumes longitudinally through the fire tubes of the boiler 1. The combustion fumes pass forwardly through the boiler 1, rearwardly between the said boiler and superheat chamber 2 and forwardly through the fire tubes of the latter, whence they pass rearwardly and are eliminated through the stack 3. Passage from the boiler 1 to the superheat chamber 2 is afforded by a connecting pipe 5 and discharge of the heated vapor or steam from the superheat chamber 2 to a heat consumer occurs through a discharge pipe 6. A fire bed 7 and grate 7a are located directly beneath the boiler 1 and the customary ash pit 8 lies directly beneath the fire bed. The shell of the boiler 1 is protected from direct contact with the heat from the fire bed 7 by a horizontal partition composed of fire brick or other suitable refractory material, but it should be noted, however, that a protective heat conducting shell may be used instead of the partition when it is desirable to avail the boiler of the direct heat from the fire.

The structure described in the preceding paragraph may be found in any of the numerous boiler installations in existence at the present time and is admittedly old. However, such boiler installations have been used to heat solid water directly in the boiler as contrasted with the particular feature of the present invention wherein water vapor (saturated air) is supplied to the boiler in place of the solid water and summarily heated and converted into steam.

The saturation of the air or other gaseous medium is accomplished in a novel manner within a vaporizing tank or chest 9 which is positioned below and insulated from the heat of the boiler. The tank 9 is substantially filled with water to a predetermined level and maintained constantly at the desired level by any well-known means such as by a float operated valve (not shown). The air or other gaseous medium is compressed by means of a compressor 10 driven by a motor 11, and the compressed air passes through a pipe 12 to a horizontal pipe 13 adjacent the bottom of the tank 9, and has a plurality of apertures therein so that the air may be discharged in small streams or jets upwardly through the body of water. To insure proper saturation of the air a pair of sprays or nozzles 14 are connected to the pipe 13 so that a substantial portion of the air entering the tank 9 may be discharged through the sprays 14, the remaining quantity of air being discharged up through the water from the apertures in the laterally extending pipe 13. It should be noted that the maximum water level height within the tank 9 is maintained at least below the level of the sprays 14 by means of a float operated valve as previously noted. A tubular collar or sleeve 15 embraces each of the sprays 14 and directs the discharge of air therefrom into the ducts 16 connected between the tank 9 and the boiler 1. A pipe 17 extends downwardly from each spray 14 into the water to within a short distance of the bottom of the tank 9, and the discharge of air from said sprays 14 creates a suction force which draws water upwardly through the pipes 17, where it is sufficiently atomized and mixed with the air to completely saturate the latter. Similarly the air passing upwardly through the water from the pipe 13 becomes saturated to a substantially high water content and forms a vapor within the tank 9 above the surface of the water.

In the present instance the spray sleeves 15 extend a small distance within the connecting ducts 16, and for the purpose of affording relatively rapid passage of the saturated vapor from the tank 9 to the boiler 1, a Venturi section is formed on the inner surface of the ducts 16 opposite the upper edges of the sleeves 15 whereby the discharging vapor from the sleeves acts to draw the saturated vapor from the tank 9, the passage of which is materially increased by the Venturi section.

The saturated vapor drawn from the tank proper and the saturated vapor discharged through the sleeves 15 mixes together while passing upwardly through the duct 16 and is discharged as a homogeneous body into the boiler 1, whence it is heated by contact with the fire tubes thereof and raised to a substantially high temperature and converted into steam in a saturated state. The saturated steam discharges through the pipe 5 to the superheat chamber 2, where it is raised to a substantial degree of superheat and high thermal efficiency, after which it exhausts upwardly through the duct 6, where it is conveyed to any heat consumer that may be used in conjunction with the particular boiler installation.

In the present instance the disclosure in Fig. 1 of the drawings is available for use in conjunction with the majority of fuel substances such as coal, coke, wood, oil or the like. However, in certain localities and regions electric energy has become sufficiently abundant as to render it avail-

able for heating and other power purposes at a cost substantially lower than other fuels, and a boiler embodying the present system of water vapor generation for use with electricity as a heating means is disclosed in Fig. 2 of the drawings, wherein the completely saturated air or other gaseous medium is provided, as in the previous instance, and discharged into a boiler 18 in which are disposed a plurality of resistance coils 19 mounted upon reflector or baffle elements 20, spaced by suitable means of insulation from the metal walls of the boiler to permit the passage of the vapor freely through said boiler. The resistances in the present instance are disposed in opposed paired relation as shown in Fig. 2 and the water vapor discharged into the boiler 18 is converted into saturated steam and summarily into the superheat chamber 21, which if desired may be similarly equipped with heating resistances in the manner shown for the boiler 18.

A particular feature of the present modification of the invention is the fact that it is possible to position the resistance heating elements within the boiler 18, and this is made possible only as a result of the gaseous rather than solid state of the saturated vapor in the boiler 18, and would not be possible were solid water used in the boiler for heating.

A further modification of the principle herein described may be had in the form of a cooling system for air or other gaseous media. The only change required by the substitution for the source of heat such as the electrical elements 19, are a number of cooling coils 22 as disclosed in Fig. 3 of the drawings.

The particular embodiments of the invention herein disclosed are capable of numerous changes and adaptations and it is not intended that the invention be limited to the disclosure if within the scope of the annexed claims.

What is claimed is:

1. In a water vapor temperature control apparatus, a heat exchange chamber, a water chest, means adjacent the bottom of said chest and operable in conjunction therewith for discharging air through the body of water therein under pressure whereby said air is saturated with moisture, and a Venturi section connecting the water chest and the chamber effecting relatively rapid discharge of the saturated vapor from said chest to said heat exchange chamber.

2. In a water vapor temperature control apparatus, a boiler, a water chest, means operable in conjunction with said water chest for discharging air through the body of water therein under pressure whereby said air is saturated with moisture, and a Venturi section connecting the water chest and the boiler effecting relatively rapid discharge of the saturated vapor from said chest to the boiler.

3. In a water vapor temperature control apparatus, a heat exchange chamber, a water chest, means operable in conjunction with said water chest for discharging air through the body of water therein under pressure whereby said air is saturated with moisture, a duct connecting the water chest and the chamber permitting passage of the saturated vapor from said chest to said heat exchange chamber, and means for controlling the temperature of the saturated vapor in the heat exchange unit.

4. In a water vapor temperature control apparatus, a boiler, a water chest, means operable in conjunction with said water chest for discharging air through the body of water therein under

5 pressure whereby said air is saturated with moisture, a duct connecting the water chest and the boiler permitting discharge of the saturated vapor from said chest to the boiler, and means adjacent the boiler and insulated from the water chest for controlling the temperature of the saturated vapor therein.

10 5. In a water vapor temperature control apparatus, a boiler, a water chest, means operable in conjunction with said water chest for discharging air through the body of water therein under pressure whereby said air is saturated with moisture, a Venturi section connecting the water chest and the boiler effecting relatively rapid discharge of the saturated vapor from said chest to the boiler, and a source of heat adjacent the boiler and insulated from the water chest for increasing the temperature of the saturated vapor in said boiler.

15 20 6. In a heat exchange system for water vapor, a heat exchange chamber, a water chest, means extending parallel to the bottom of said chest and connected to an air compressor for discharging a number of small jets of air through the body of water in the chest, spray means residing above the water level within the chest and connected to the first-named means for discharging at least a portion of the air therefrom which enters said chest, a siphon extending from the spray downwardly into the water and whereby water is drawn into the stream of air discharging from the spray and mixed therewith, and a Venturi section surrounding the discharge end of the spray in spaced relation with respect thereto whereby the saturated vapor in the chest proper is drawn therefrom and discharged at a relatively rapid rate for mixture with the saturated air discharging from the spray, passing into the heat exchange chamber.

25 30 35 40 45 7. In a heat exchange system for water vapor, a heat exchange chamber, a water chest, a pipe having a plurality of apertures therein and connected to an air supply pipe and connected to an air compressor for discharging a number of small jets of air through the body of water in the

5 chest, spray means residing above the water level within the chest and connected to the first-named means for discharging at least a portion of the air therefrom which enters said chest, a siphon extending from the spray downwardly into the water and whereby water is drawn into the stream of air discharging from the spray and mixed therewith, and a Venturi section surrounding the discharge end of the spray in spaced relation with respect thereto whereby the saturated vapor in the chest proper is drawn therefrom and discharged at a relatively rapid rate for mixture with the saturated air discharging from the spray, passing into the heat exchange chamber.

10 15 20 25 30 35 40 45 5. In a water vapor temperature control apparatus, a heat exchange chamber, a water chest, means operable, in conjunction with said water chest for discharging air through the body of water therein under pressure whereby said air is saturated with moisture, and a connection between the water chest and the heat exchange chamber permitting passage of the saturated vapor from said chest into said chamber.

6. In a water vapor temperature control apparatus, a heat exchange chamber, a water chest, means adjacent the bottom of said chest for discharging a plurality of small jets of air through the body of water in the chest whereby said air is saturated with moisture, and a connection between the water chest and the heat exchange chamber permitting passage of the saturated vapor from said chest into said chamber.

7. In a water vapor temperature control apparatus, a heat exchange chamber, a water chest, means operable in conjunction with said water chest for discharging air through the body of water in the chest whereby said air is saturated with moisture, a duct connecting the water chest and the heat exchange chamber, and means also in said chest constructed and arranged to discharge saturated vapor into said duct whereby the saturated vapor in the chest proper is drawn into combination therewith and discharged into the heat exchange chamber.
